RADIO TRANSMISSION AND RECEPTION

Harry B. Breedlove, Memphis, Tenn.

Application September 25, 1935, Serial No. 41,986

11 Claims. (Cl. 250—10)

This invention relates to means and methods for removing or suppressing interference, including static, which interferes with the reception of signalling currents transmitted at radio frequencies, either over wire, air or other non-metallic circuits. It relates to the suppression or removal of such interference in complete wire circuits, wire and non-metallic return circuits, or radio broadcasting and receiving circuits.

10 It primarily relates to means and methods for utilizing two of the usual bands of frequencies which bands preferably are adjacent bands, for transmitting and receiving signals at radio frequencies, the interference on one band being used to suppress the interference on the other thereof.

15 It further relates to means and methods for utilizing two of the usual bands of frequencies for receiving signals at radio frequency, one of such bands being unused, at least locally, so far as transmitting is concerned, or modulated in such a manner that its signal may be filtered out, the interference on one band being used to suppress the interference on the other band.

20 It further relates to means and methods for utilizing a plurality of bands of frequencies for receiving signals at radio frequency, one of which bands is left unused at least locally, so far as sending is concerned, or is modulated in such manner that its signal may be filtered out, the 25 interference on such unused band being used to suppress the interference on each of the other bands.

25 It further relates to the utilization of two bands of frequencies, which preferably are adjacent bands, and to means and methods for concurrently transmitting a signalling current at radio frequency over such bands, the transmission bands being energized at their respective frequencies and being jointly intensity-modulated out-of-phase, and in receiving these out-of-phase currents, so combining them that the signalling currents of one band supplement the opposite-phase signalling currents of the other thereof, while 30 unwanted interference currents that may enter the receiver on one band will oppose and cancel out the inherently in-phase interference currents that enter on the other band.

35 It is further directed in receiving signalling currents at radio frequency, toward the utilization of two bands of frequencies, one of which bands may be locally-vacant only and in so combining the currents that unwanted interference current intensity which may enter the receiver on one band will oppose and suppress the inherently 40 in-phase interference current intensity on the

other band; whereas the signalling current intensity of the used band will be opposed by no-signalling current intensity in the signal vacant band.

45 In usual transmission at radio frequency a carrier wave of desired frequency, intensity modulated, is suitably amplified, and is transmitted from the sending antenna, such carrier waves when received being often accompanied by static or other interference which hinders, or even prevents reception.

50 In the preferred form of my device two such carrier waves, preferably though not necessarily, of adjacent frequencies are jointly but inversely intensity modulated, so that one wave is preferably at its maximum intensity at the same time the other is at its minimum intensity. The two waves suitably amplified, are sent out over a joint antenna or two separate antennae, the two waves so sent out, as is inherently true of all radio frequency waves, not combining their frequencies or their intensities.

55 The two waves so sent out are picked up, still in inverse phase in intensity, by a single antenna, or by two antennae of the receiving instrument. If 25 picked up by a single antenna they may both be jointly tuned, amplified, detected, or converted, and if desired, beat with a signal from a local tuned oscillator, and the two frequencies received, or produced, as the case may be, separately passed through desired amplifying stages to detectors 30 wherein they are each changed into audio frequency currents. These inverted audio frequency currents are then so combined in the primary of 35 a transformer that the two out-of-phase intensities supplement each other, and jointly induce a current which is amplified and sent out over the speaker. At the same time interference currents may enter the receiver with both of these currents, and pass therethrough in the same manner, the intensities of such interference however being inherently in-phase, so that the two intensity 40 phases oppose each other and the interference is cancelled out or at least to a major extent suppressed.

45 Or the two waves whether received by a single antenna or two antennae may be separately tuned, amplified, converted, heterodyned if desired, and passed to and through detectors, the output of 50 these detectors being combined as before.

55 In reception also it is possible to receive a carrier wave sent out in usual manner at a single frequency and suppress interference thereon provided there is available at the receiving point a channel or carrier wave which so far as that

particular receiving instrument is concerned is signal-vacant; that is, does not bring into the instrument a signal but which inherently does bring in interference in the same manner as does 5 the signal bearing current.

In reception therefore, the invention makes use of two channels at different frequencies, which channels may be adjacent frequency bands, or separated frequency bands, both channels may 10 have signal energy impressed thereon, which energy has been modulated in intensity in out-of-phase relation; or one channel may be signal-vacant, and the other thereof signal-bearing, and intensity modulated. In the latter case the 15 signal-vacant channel may be signal-vacant locally only. In either case the receiving apparatus is adapted to receive and be tuned, independently if necessary, to the two channels then being used. Interference, if existent, having its own carrier 20 waves enters the receiving apparatus substantially equal on both the signal-vacant channel and the signal bearing channel. The intensities of the two signal frequencies are then combined in reinverted phase relation, so that the two signal 25 intensities are now supplemental or the single signal intensity is unopposed and the signal comes in in full value, while the interference intensities of the channels oppose and cancel out, one the other.

30 While a locally signal-vacant channel may be used, a channel left vacant by all stations in sending is preferred, and where this is done one signal-vacant channel may be used with a number of signal-using or transmitting channels.

35 It is preferable in reception that the two channels, both signal carrying, or one signal carrying and one vacant, be adjacent. In the standard (long wave) broadcast band this is probably now not possible and such locally signal-vacant channel as may be available must be found and used. In the next higher bands of frequencies however cleared channels may probably be available, though it may be necessary to have one such cleared channel for a number of sending 40 stations, but in the high frequency or short wave bands it appears feasible to clear for each sending station two adjacent bands one of which may be used or left unused as may appear advisable to such station.

50 The objects of the present invention are:

To provide means and methods of suppressing interference including static in the reception of signalling energy at radio frequency, either over wire, the air, or other circuits.

55 To provide means and methods for so transmitting and receiving signalling energy at radio frequency either over wire, the air or other circuits, that interference, including static may be cancelled out or suppressed.

60 The means by which the foregoing and other objects are accomplished and the method of their accomplishment may readily be understood from the following specification on reference to the accompanying drawings, in which,—

65 Fig. 1 illustrates the general arrangement of one form of the transmitter, using a single antenna.

Fig. 2 an arrangement for superheterodyne reception, using a single antenna, tuner and converter, and

Fig. 3 a specific hookup between the detectors and the audio frequency amplifier and speaker.

Fig. 4 illustrates an arrangement for tuned radio frequency reception, using a single antenna 75 and separate tuned radio frequency stages.

Fig. 5 illustrates an arrangement for heterodyne reception, using independent antennae and separate tuning and heterodyning channels.

Fig. 6 illustrates an arrangement for tuned radio frequency reception using a plurality of 5 antennae each feeding a tuned radio frequency channel.

Fig. 7 illustrates a modified arrangement of transmitter using two antennae.

Fig. 8 is a further modified arrangement of 10 transmitter in more specific detail, also using two antennae; and

Fig. 9 a third modification, also in specific detail, using a single antenna.

Referring now to the drawings in which the 15 various parts are referred to by numerals;

In Figs. 1, 2 and 3; 10 and 11 are constant frequency oscillators operating at different frequencies, which impress their energy on radio frequency amplifiers 12 and 13 respectively. 20 Leads 14 and 15, complete through radio frequency transformer primaries 16, 17 and modulator transformer secondary 18, a circuit from one phase side of amplifier 12 to the opposite phase side of amplifier 13. A center tap 19 and 25 leads 20, 21 complete the circuits to the amplifiers. 22 is a modulation amplifier connected to the primary 23 of the modulation transformer and which feeds the modulation system. The secondaries 24, 25 of the radio frequency transformers are connected to radio frequency amplifiers 29 and 30 respectively, and the signals of said amplifiers are impressed upon a conventional antenna system 33, 34 and 35 by coils 31 and 32.

35 The receiver includes a conventional antenna system 40, 41, a tuned radio frequency amplifier 42, the output of which is connected to a first detector or converter 43, and there mixed with local tuned oscillator signals from an oscillator 44. 40 Output of detector 43 is connected to two intermediate frequency amplifiers 45 and 46, which are tuned to frequencies having the same differences as that between the oscillators 10 and 11. The outputs of amplifiers 45 and 46 are further amplified by intermediate frequency amplifiers 47 and 48 respectively, and the outputs of these latter amplifiers are fed into second detectors 49 and 50 respectively. 45

The outputs of detectors 49 and 50 are connected to the opposite ends of the primary 51 of a transformer. The center of this primary is connected back to both detectors. The secondary 52 of the transformer is connected to amplifier 53 and the output of this amplifier is impressed 55 on speaker 54.

Fig. 3 shows a specific hook-up between the detectors 49 and 50 and the amplifier 53. In this modification the output of detector 49 is connected through a push pull transformer 55 to the grids of electron discharge devices 56, 57, and the detector 50 is connected in inverse phase relation through push pull transformer 58 to the grids of electron discharge devices 59 and 60. The plates of electron discharge devices 56 and 59 are connected to one side of primary 51 of a third transformer, and the plates of electron discharge devices 57 and 60 are connected respectively to the opposite sides of the primary 51 of the third transformer. Secondaries of the push pull transformers and primary of third transformer are tapped and connected back to heating elements or cathodes, of the electron discharge devices.

70 In this type of the device shown in Fig. 1 two 75

carrier waves unmodulated are generated of different frequencies by oscillators 10 and 11, and passed separately in usual manner through amplifiers 12 and 13, to the primaries 16 and 17 of transformers in which they are modulated, inversely as to intensity, by modulation transformer 18-23. The modulated waves from secondaries 24 and 25, of the transformers are impressed on amplifiers 29 and 30 respectively, and placed on the antenna system, 33, 34 and 35, thereby being transmitted.

The waves thus sent out are picked up still in inverse intensity by antenna system 40, 41 tuned and amplified by amplifier-tuner 42, impressed upon converter 43, and beat with signal from a local tuned oscillator 44. The beat frequencies caused by the difference of the incoming signals and the local oscillator produce through these converters two frequencies or heterodynes, the difference of which frequencies is equivalent to the difference in frequency of the two transmitted waves. These two heterodyne signals are amplified and tuned through separate channels 45-47 and 46-48 to second detectors 49 and 50, the signals remaining of inverse intensity. Outputs of detectors 49, 50 pass through primary 51 of the transformer, thereby creating the usual maximum inductance in secondary 52, and thence to amplifier 53 and speaker 54.

During the cycle thus described, static or other interference which may be received and amplified is carried by both of the channels at substantially equal intensity, this intensity on both channels being in phase and being received with the incoming signals one of which is of opposite phase. Interference passes with such signals to the transformer 51-52, but being of the same phase, the phases are opposed in the primary 51 and thereby induce a minimum, if any current in secondary 52, and for practical purposes are eliminated, whereas the out-of-phase signal currents, supplement one the other and create maximum induction.

In the modification shown in Fig. 3 the output of the detector 49 passes to the push pull transformer 55 and from the transformer 55 to the electron discharge devices 56 and 57. The interference current and the signal current relatively out-of-phase pass from the detector 50 to the push pull transformer 58 and thence to the electron discharge devices 59 and 60. From the electron discharge devices 56-59 and 57-60 the current flows to the primary of the transformer 51-52; the interference currents being in-phase oppose each other and create a minimum current flow; whereas the signal currents being of opposite phases create a maximum current flow in the primary 51, and these flows induce corresponding currents in the secondary 52, the interference currents being for practical purposes eliminated and the signal currents carried through at a maximum intensity to the amplifier 53 and the speaker 54.

In Fig. 4 a tuned radio frequency receiving system is shown which uses a single receiving antenna 70, 71 and two tuning amplifying channels employing tuner-amplifiers 72-74-76 and 73-75-77 respectively, and detectors 78, 79, the output from the detectors passing through transformers 80, 81, the secondaries 82, 83 of the transformers being inter-connected in inverted phase relation and jointly leading to an audio frequency amplifier 84 and speaker 85.

In Fig. 5 a receiving system of super-heterodyne type is shown in which two frequencies are

received over independent antennae and separately tuned and amplified. 90, 91 respectively are the antennae systems 92, 93 radio frequency tuner-amplifiers in which radio frequency currents are taken from the antennae systems tuned and amplified independently. 94, 95 are local oscillators which are tuned independently and 96, 97 converters. 98-99, 100-101 are tuned intermediate frequency amplifiers and 102, 103 are detectors. Detectors 102 and 103 are connected by leads 104, 105 through condensers 106, 107 to opposite ends of the primary 108 of a transformer. A center tap 109 connects the primary 108 through joint return leads 110, 111 to the opposite sides of the detectors 102, 103 respectively. Leads 104, 105 are bridged by a resistance 112, from which a variable tap 113 is also lead to the joint return circuits 110, 111. 114 is the secondary of the transformer, 115 an audio frequency amplifier and 116 the speaker.

Fig. 6 is a receiving system of the tuned radio frequency type using a plurality of antennae and a plurality of channels, one of the channels being vacant insofar as sending is concerned. 120 is a conventional tuner-amplifier which may be independently tuned to the desired frequency of a transmitting station. 121 is a similar tuner-amplifier, which may be tuned to the frequency of a second transmitting station and 123 is a further similar tuner-amplifier which may be tuned to the frequency of a signal-vacant channel, such channel being either a fully cleared or at least locally-vacant one. 124, 125 and 126 are detectors for the respective channels. 127 and 128 are respectively audio frequency amplifiers connected 30 respectively to the output of detectors 124 and 125; and 129, 130 are similar audio frequency amplifiers connected to the output of detector 126. The outputs of amplifiers 127 and 129 are connected to opposite ends of a variable resistor 131 and also the condensers 141-142 to the opposite ends of the primary 132 of a transformer. Similarly the outputs of amplifiers 128 and 130 are connected to the opposite ends of a variable resistor 133 and also through condensers 143-144 to the opposite ends of the primary 134 of the transformer, these connections and the remaining connections being similar to those shown in Fig. 5; 135, 136 being the secondaries respectively of the two transformers. 137, 138 are audio 50 frequency amplifiers and 139, 140 speakers.

In Fig. 7 a modification is shown in which 150, 151 are constant frequency oscillators operating at different frequencies, which impress their energy on radio frequency amplifiers 152, 153 respectively.

The outputs of these amplifiers is connected to transformers 156 and 157 respectively then to opposite ends of the secondary 158 of a modulation transformer, the center tap 159 of this transformer being connected back to amplifiers 152 and 153, and the primary 160 being connected to a modulation amplifier 154. The secondary of transformer 156 is connected to an antenna system 161, 162 and the secondary of transformer 157 to an antenna system 163, 164. 165 represents the source of the modulation energy of amplifier 154.

Fig. 8 is a schematic drawing showing the hookup of a transmitter employing two antennae. 170 and 171 are variable condensers. 172 and 173 are tapped coils. 174 and 175 are resistances. 176 and 177 are electron discharge devices. 178 and 179 are variable condensers. 180 and 181 are coils. The parts 170, 172, 174, 176, 178, 180

constitute one tuned oscillator and the parts 171, 173, 175, 177, 179 and 181 a similar tuned oscillator. 182 and 183 are sources of electrical energy which operate the two oscillators jointly. 184 and 185 are radio frequency chokes. 186 and 187 are variable condensers. 188 and 189 are electron discharge devices. 190 and 191 are variable condensers. 192 and 193 are the primaries of radio frequency transformers. 194, 195, 196 are sources of electrical energy which operate these parts jointly. The parts 184, 186, 188, 190 and 192 form one radio frequency amplifier and the parts 185, 187, 189, 191 and 193 a similar radio frequency amplifier. The two amplifiers just described are connected to opposite ends of the secondary 197 of a modulating transformer, the center of which secondary is connected to the source of electrical energy 196. The primary 198 of the modulation transformer is connected to a source of modulation energy (not shown), by leads 199. The secondaries 200, 201 of the radio frequency transformers are connected to conventional antenna systems 202, 203 and 204, 205 respectively, being tuned by variable condensers 206, 207.

Fig. 9 is a schematic diagram of a transmitter using a single antenna system, and also using crystals in the oscillator circuits. In these circuits 220 and 221 represent crystals. 222 and 223 are resistors which bridge the leads from these crystals, 224 and 225 are electron discharge devices. 226 and 227 are respectively the primaries and 228, 229 the secondaries of two radio frequency transformers, the primaries 226 and 227 being respectively tuned by variable condensers 230, 231. The parts 220, 222, 224, 226 and 230 form one fixed frequency oscillator, and the parts 221, 223, 225, 227 and 231 form a similar fixed frequency oscillator. The two oscillators being adapted to operate at different frequencies. 232 and 233 are the primary and secondary respectively of a modulation transformer, and 234 and 235 are sources of electrical energy which energize the two oscillators. The primaries 226, 227 of the radio frequency transformers are connected to opposite ends of the secondary 233 of the modulation transformer.

236, 237; 238, 239; and 242 and 243 are variable condensers and 240, 241 are electron discharge devices. 244, 245 are coils. The secondary 228 has its leads bridged through the variable condenser 236, the electron discharge device 240 is neutralized by the condenser 238, and the coil 244 with its leads is bridged through the variable condenser 242, these parts forming one radio frequency amplifier; and the similar secondary 229, electron discharge device 241 and coil 245 with their connecting leads are similarly bridged and neutralized by condensers 237, 239 and 243, forming a second radio frequency amplifier. These two amplifiers are coupled by joint leads 246 and 247 tapped into and leading respectively from the coils 244, 245, and through the energy sources 249, 250 and 251 which operate the two amplifiers. 256 is a microphone or other source of modulation energy. 257 is a coupling transformer and 258 an electron discharge device which is connected to the primary 232 of the modulation transformer. 252 is a coil which is inductively coupled to the coils 244 and 245. 253 and 255 are an antenna system bridged by a variable condenser 254.

It will be distinctly understood that tuned radio frequency receivers such as are indicated in Figs. 4 and 6 or superheterodyne receivers such as

are shown in Figs. 2 and 5, may be used interchangeably in all of the modifications.

It will also be understood that the receiver systems in the main may consist of two standard tuning amplifying and detecting systems inversely connected and delivering to a single speaker.

It will also be understood that variably tapped resistance bridges similar to the resistance bridges 112, of Fig. 5 and the resistance bridges 131 or 133 of Fig. 6 may be introduced in the forms of 10 receivers shown in Figs. 2 and 4 should it be so desired.

Operation, transmission

In transmitting, using any of the transmitter forms shown, two carrier waves suitably energized as by the energy sources 182, 183 of Fig. 8 or the energy sources 234, 235 of Fig. 9 are passed through the two oscillators and two differing desired frequencies determined in the waves by the two oscillators. Should it be feasible these two frequencies are adjacent frequencies so spaced that when properly modulated in intensity the intensity swings do not overlap. In other words the two frequencies respectively lie each in a transmission band such as is established and allotted under present conditions to a sending station. While these frequencies are preferably adjacent they may be separated, that is, have other frequency bands intervening. The two carrier waves thus established are then separately amplified in usual manner as in the amplifiers 12, 13 of Fig. 1; 152, 153 of Fig. 7; or the amplifiers of Fig. 8, and are jointly modulated inversely in intensity by energy from the modulation amplifiers 22 of Fig. 1; 154 of Fig. 7; or from the modulator not shown brought in through the leads 199 of Fig. 8, this inversion of intensity being accomplished by reason of the opposite connection of the secondary 18 of the modulation transformer to the primaries 16 and 17 of the radio frequency transformers, Fig. 1; the similar connection of the radio frequency transformers 156, 157 of Fig. 7, through the secondary 158 of the modulation transformer in Fig. 7; or the like connection of the primaries 192, 193 of the radio frequency transformers through the secondary 197 of the modulation transformer in Fig. 8; and after such intensity inversion, the intensity frequencies set up in the secondary of these radio frequency transformers as intensity modulated are sent out over the antenna system which may be either a single antenna or two antennae as may be desired.

In Fig. 1 radio frequency amplifiers are introduced between the radio frequency secondaries and the antenna system and these may be similarly introduced in the form shown in Figs. 7 and 8 though they have not been so shown.

In Fig. 9 the same essential steps are followed, except that the frequency waves are not amplified before being modulated in intensity but are amplified after such modulation and before placing on the antenna system.

Transmission for any of the forms of reception herewith may also be accomplished by any standard intensity modulated transmission system of the present type provided only there be a signal-vacant channel available at the receiving end. In furtherance of this, a transmitting station having two channels available for transmission 70 may make use of one only thereof, leaving the second channel signal-vacant, and in such case, additional transmitting stations may avail themselves of the same signal-vacant channel, such signal-vacant channel being available for use in 75

reception from any one of such stations. It is preferable that the two channels used be adjacent. An extremely desirable condition in such case would be a vacant channel lying adjacent to and between two signal-used channels whereby each signal-used channel will have an adjacent signal-vacant channel. In such case also the signal-vacant channel would also be available for other signal-using channels. In the absence of a channel signal-vacant throughout, a channel locally signal-vacant may also be used.

Operation, reception

In reception two carrier waves of differing frequency, jointly modulated in inverse intensity by one signal modulator may be received over a single antenna as shown in Figs. 2 and 4 or over separate antennae as shown in Figs. 5 and 6.

In Fig. 2, two radio frequency carried waves, modulated inversely in intensity, received over the antenna system 40, 41, are broadly tuned by radio frequency amplifier tuner 42 and passed to a converter or first detector 43, and there beat with a signal from a local tuned oscillator 44, the output of the converter being separated and passed in parallel through intermediate frequency amplifiers 45, 46; 47, 48 to detectors 49, 50 respectively, each frequency being in these channels amplified, tuned, filtered and detected in the usual manner. The audio frequency currents set up in the detectors are still in out-of-phase intensities as they were sent out from the transmitter and due to the inverted hookup of the detectors 49, 50 are re-inverted into complementary phase relation in the primary 51, inducing a current which is amplified and sent out through the speaker 54. If static or interference exists, having its own carrier waves, it is received on the antenna system and is broadly tuned by the tuner amplifier 42, those frequency currents corresponding to the frequency of the signal carrying waves being passed to the converter and beat with the signal from the local tuned oscillator. The mixed outputs from the converter separate and pass in the same manner as the signal carrying currents in parallel, through the two sets of intermediate frequency amplifiers, to the detectors 49, 50 wherein they also are changed into audio frequency currents. These interference currents however having been received on the antenna inherently in in-phase intensities, the intensities of the interference audio frequency outputs of the detectors, are also in-phase and entering opposite ends of the transformer primary 51 therefore oppose each other, cancelling the one the other out so that substantially none of the interference intensities are available to interfere with the signal output of the speaker.

In Fig. 4 substantially the same action occurs except that the two intensity inverted signalling frequencies, each accompanied by an interference frequency, are individually tuned, amplified and detected, the detector outputs being combined as before and passed to the speaker; and the same condition occurs in the form shown in Fig. 5 with the exception that reception is over two antennae instead of over one antenna.

In Fig. 5 however (and also in Fig. 6), the outputs from the detectors 102, 103 passing to the primary 108 may be balanced either in so far as the signalling frequencies are concerned, or in so far as the interference is concerned by adjusting the tap 113 relatively to the resistance bridge 112. Particularly therefore where the frequency channels are not adjacent and the inter-

ference intensities are unequal, it is possible by shifting the relation of the tap and the bridge, to so balance the interference that the two opposing phases are equal and actually balance out. This shift may unbalance the signalling currents but since such currents are supplemental, in no way affects clear reception of such currents.

The form shown in Fig. 6 is only usable with a cleared or locally vacant channel and with single channel transmission. In this form, intensity modulated signalling waves from one station and interference waves are received, tuned and detected through tuner-amplifier 120, and detector 124, and from the same or another station through tuner-amplifier 121, and detector 125, and the detected outputs delivered through amplifiers 127, 128 respectively to the primaries 132, 134. Interference waves unaccompanied by signalling waves are received tuned and detected by, tuner-amplifier 123 and detector 126, and the detector output delivered in parallel through amplifiers 129, 130 to the opposite ends of the two primaries 132, 134 respectively, this interference being balanced by the variably tapped bridges 131, 133, in the respective primaries, and cancelling out the opposed phase interference in such primaries, leaving the signalling currents to pass unopposed and induce current in their respective secondaries, which are amplified and sent out through the speakers. It will be understood that while two signal-wave receivers only are shown, these are merely typical of a plurality of such receivers, all of which may be interference cleared by a single signal-vacant receiver.

In any of the forms of the device, including Fig. 6, signalling currents may be received from a transmission system of usual type sending out the usual single band of intensity modulated signal carrier waves. In such case, as for example, in Fig. 2, the signal carrier wave accompanied by an interference carrier wave of like frequency received over the antenna, leaves the tuner amplifier 42 and a second interference carrier wave of different frequency unaccompanied by a signal current, also leaves such tuner and are all detected and beat with the signal from the local tuned oscillator 44 and the outputs passed in parallel through the intermediate frequency amplifiers 45-47, and 46-48 to the detectors 49 and 50 respectively, the output of one detector carrying interference and signal, and the output of the other detector carrying interference only. The outputs of these two detectors then combine in inverted relation, in the primary 51 of the transformer, the two interference current intensities opposing and cancelling one the other, and the signal intensity being unopposed passing to the speaker.

It will be understood that the amplifiers 127, 128, 129 and 130, shown in Fig. 6 prevent feed back from the coils 132, and 134 through the circuits that lead thereto from the several detectors 124, 125 and 126, and thereby prevent interference between programs received over the various circuits.

What I claim is:

1. In a receiver for intensity modulated radio frequency currents and which employs tuning and amplifying means, dual detectors, each having an output transformer, two pairs of electron discharge devices, a third transformer, having its primary inverted with relation to the primary of one said output transformer; and an amplifier and speaker connected to the secondary of said third transformer; means connecting opposite

ends of the secondary of a first said output transformer respectively each to the grid of a first said electron discharge device of each said pair of said devices, means connecting opposite ends of the secondary of the second said output transformer respectively each to the grid of the second said electron discharge devices of each said pair of said devices, means connecting both plates of a first said pair of said devices and 10 both plates of the second said pair of said devices respectively to opposite ends of the primary of said third transformer, interconnected taps connecting the secondaries of both said output transformers to the cathodes of said electron devices, and a tap connecting the primary of 15 said third transformer to said cathodes.

2. In a receiver for intensity modulated radio frequency currents and which employs tuning and amplifying means, dual detectors, each having an output transformer, electron discharge means in duplicate, each means having a pair of grids and a plate, a third transformer, having its primary inverted with relation to the primary of one said output transformer; and an 20 amplifier and speaker connected to the secondary of said third transformer; means connecting opposite ends of the secondary of a first said output transformer respectively to a first grid of a first said electron discharge means, and a 25 first grid of the second electron discharge means, means connecting opposite ends of the secondary of the second said output transformer respectively to the second grid of said first electron discharge means, and the second grid of said second 30 electron discharge means, means connecting the said plates of said first and second said electron discharge means respectively to opposite ends of the primary of said third transformer, interconnected taps connecting the secondaries of 35 both said output transformers to the cathodes of said electron devices, and a tap connecting the primary of said third transformer to said cathodes.

3. Means for suppressing interference in radio 45 reception, including means for establishing at least three channels, each for tuning and detecting a carrier wave of desired frequency, means for combining the output of one of said channels in out of phase intensity relation severally with the output of each of the others of said channels respectively, and means for independently delivering the unopposed signal output of each of the latter said channels.

4. Means for suppressing interference in radio 55 reception, including means for establishing at least three channels, each for tuning and detecting a carrier wave of desired frequency, means for combining the output of one of said channels in out of phase intensity relation severally with the output of each of the others of said channels respectively, means for preventing feed back from each of said channels to another thereof, and means for independently delivering the unopposed signal output of each of the latter said channels.

5. Means for suppressing interference in radio 60 reception, including means for establishing at least three channels, each for tuning and detecting a carrier wave of desired frequency, means for combining the output of one of said channels in out of phase intensity relation severally with the output of each of the others of said channels respectively, said combining means including means for severally adjusting each said phase relation, and means for independently delivering 65

the unopposed signal output of each of the latter said channels.

6. Means for suppressing interference in receiving waves at radio frequency, which includes using at least three receiving means, each having means for independently tuning, amplifying and detecting a modulated carrier wave, means for mixing the detected output of one said receiving means severally with the detected outputs of each of the others of said receiving means in phase relation to cause the intensity phase of the interference modulations of the carrier wave received on the one said receiving means to oppose the intensity phase of the interference modulations of the carrier waves received on each of the other said receiving means, whereby in each to substantially cancel out said interference; and means for subsequently independently amplifying and delivering the unopposed signal output of each of the latter said receiving means. 20

7. Means for suppressing interference in receiving waves at radio frequency, which includes using at least three receiving means each having means for independently tuning, amplifying and detecting a modulated carrier wave, means for 25 mixing the detected output of one said receiving means severally with the detected outputs of each of the others of said receiving means in phase relation to cause the intensity phase of the interference modulations of the carrier wave received on the one said receiving means to oppose the intensity phase of the interference modulations of the carrier waves received on each of the other said receiving means, means for severally adjusting said phase relations, whereby in each to 30 substantially cancel out said interference; and means for subsequently independently amplifying and delivering the unopposed signal output of each of the latter said receiving means. 35

8. Means for suppressing interference in receiving waves at radio frequency, which includes using at least three receiving means, each having means for independently tuning, amplifying and detecting a modulated carrier wave, several means for mixing the detected output of a first of 45 said receiving means with the detected outputs of each of the others of said receiving means respectively in phase relation to cause the intensity phase of the interference modulations of the carrier wave received on the first said receiving means to oppose the intensity phase of the interference modulations of the carrier waves received on each of the other said receiving means, circuits, leading severally from the detecting means of said first receiving means each to a 55 said mixing means, circuits leading from the said detecting means of said other receiving means each to a said mixing means, and amplifiers, interposed one in each of said circuits.

9. Means for suppressing interference in receiving waves at radio frequency, which includes using at least three receiving means, each having means for independently tuning, amplifying and detecting a modulated carrier wave, several means for mixing the detected output of a first of 60 said receiving means with the detected outputs of each of the others of said receiving means respectively in phase relation to cause the intensity phase of the interference modulations of the carrier wave received on the first said receiving means to oppose the intensity phase of the interference modulations of the carrier waves received on each of the other said receiving means, circuits, leading severally from the detecting means of said first receiving means, each to a said mix- 65

75

ing means, circuits leading from the detecting means of said other receiving means each to a said mixing means, and means interposed, one in each said circuit for preventing feed back from its related mixing means therethrough.

5 10. The method of suppressing interference in receiving waves at radio frequency, which includes tuning, and detecting a carrier wave intensity modulated by unwanted interference free from signal modulation; independently tuning, and detecting a plurality of carrier waves at different frequencies, each said wave intensity-modulated by a desired signal and by unwanted interference, and mixing the detected output of 10 said signal free wave severally with the detected outputs of each of the others of said waves in phase relation to cause the intensity phase of the said signal free wave to oppose the intensity phase of the interference modulations of each of the other thereof, whereby in each to substantially cancel out said interference; and subsequently severally amplifying and delivering the unopposed signal outputs.

11. The method of suppressing interference in receiving waves at radio frequency, which includes tuning and detecting a carrier wave intensity modulated by unwanted interference free from signal modulation, independently tuning and 5 detecting each of a plurality of carrier waves at different frequencies, each said wave intensity-modulated by a desired signal and by unwanted interference, mixing the detected output of said signal free wave severally with the detected outputs of each of the others of said waves in phase relation to cause the intensity phase of the said signal free wave to oppose the intensity phase of the interference modulations of each of the other thereof and severally adjusting said phase relations, whereby in each to substantially cancel out 10 said interference; and subsequently severally amplifying and delivering the unopposed signal outputs. 15
